UNITED STATES PATENT OFFICE.

GEORGE P. BOSWORTH, OF CENTRAL FALLS, RHODE ISLAND, ASSIGNOR, BY MESNE ASSIGNMENTS, TO HEMPHILL COMPANY, OF CENTRAL FALLS, RHODE ISLAND, A CORPORATION OF MASSACHUSETTS.

STOCKING-KNITTING MACHINE FOR MAKING ANTIRAVELING COURSES.

1,377,460.

Specification of Letters Patent. Patented May 10, 1921.

Application filed February 13, 1915, Serial No. 8,011. Renewed December 22, 1917. Serial No. 208,530.

To all whom it may concern:

Be it known that I, GEORGE P. BOSWORTH, citizen of the United States, residing at Central Falls, Rhode Island, have invented 5 certain new and useful Improvements in Stocking-Knitting Machines for Making Antiraveling Courses, of which the following is a specification.

One object of my invention is to provide 10 means for producing a course of knitting in a stocking leg to prevent raveling below the point where this course is thrown in, say, about at the top of the calf.

The invention is capable, however, of 15 other uses, and it will be understood therefore that the invention is not limited to the production of the specific fabric mentioned.

My invention, while shown in connection 20 with a hosiery machine of the type known as the "Banner" made under United States Letters Patent of Hemphill, #933,443, September 7, 1909, is not limited in its application to a machine of this make.

The invention is shown in the accompanying drawings in which—

Figure 1 is a developed view of the needle cams, and the needles and jacks.

Fig. 2 illustrates long and short butt needles and a jack, a set of each of which 30 is employed in this machine.

Fig. 3 is a diagrammatic plan view of the machine with the parts set for performing ordinary plain knitting, this view being different from Fig. 1 in this respect in that 35 in Fig. 1 the cams are set to make the special course to prevent raveling.

Fig. 4 is a diagrammatic view showing one of the cams with the connections for automatically adjusting the same and the 40 connections for controlling the yarn feed.

Fig. 5 is a perspective view of the needle lifting cam which is active during heel and toe work.

Fig. 6 shows long and short butt needles 45 alternate ones of which in the needle circle are provided with long tails instead of being operated by jacks.

Fig. 7 is a view of part of a needle cylinder with a needle cam and one of the long 50 tail needles which coöperate therewith.

Fig. 8 is a diagrammatic view of the stocking produced by my invention.

In application for Letters Patent of the United States filed by me August 31, 1914,

#859,492, I disclose means for making a 55 non-raveling course by advancing every other needle to knit while the other needles are held retracted in a low plane, and thus are prevented from taking the yarn, these needles simply holding their stitches during 60 this round, after which these needles are brought into work again and knitting of the ordinary fabric is continued on all the needles to form the stocking in the usual way. In my present invention the other 65 needles which do not knit are controlled to make tuck stitches.

In the drawings, 1 is the needle cylinder which rotates in the direction of the arrow. The needles are in two sets, one set of long 70 butts *a* and one set of short butts *b*, each set occupying one-half of the needle circle. Narrowing picks are shown at 2, widening picks at 3, stitch cams at 4, 4', guard cam at 5, instep cam at 6, and instep lowering 75 cam at 6', all as in ordinary practice in the machines of the Banner type.

In knitting a stocking on my machine the garter top and the upper part of the leg are made in the ordinary way to the point at or 80 above the calf of the leg at which it is desired to stop raveling should this occur, so that if raveling starts above this point it will be stopped here and prevented from going below this point.

In order to provide a course of knitting at the desired point to arrest or stop raveling, I employ a cam arrangement which will divide the needles, allowing every other needle throughout the needle circle to knit 90 while the other needles are advanced only far enough to take the yarn but not far enough to get their old loops below their latches; the result being that on these other needles tuck stitches will be formed in this 95 non-raveling course, the advantage of which is that the fabric here will have a high degree of elasticity and will not be subject to breakage.

For controlling the needles to make this 100 non-raveling course I divide them just before they reach the thread feed so that only every other needle will rise to clear its loop below its latch. For this purpose I provide a lowering cam 7 which is shiftable radially 105 in relation to the needle cylinder, and when this is in its innermost position it lies close to the needle cylinder so that all the needles

will be lowered from their normal plane, as indicated by the knitting wave at *c*, Fig. 1. For this purpose the cam ring 8 is cut down at 9 so that the needle butts may travel 5 down this incline on the under side of the cam 7. The normal plane of the needle butts is indicated at *d*. I also provide the cam ring 8 with a pivoted section at 10, this being the portion which, by its inclined 10 edge 11 in ordinary practice during reciprocating knitting, serves to return or lift the needles to their normal plane indicated by the character *d*.

This section is ordinarily rigid and in 15 one with the cam ring 8, but with my improvement it is formed separately and is pivoted to the main portion of the cam ring at 12. It is under tension of a spring 13 tending to hold it in normal position with 20 its incline 11 in the path of the needles.

As shown in Fig. 3, the main body of the cam is inclined in relation to the needle circle, presenting a side at 13° which extends at an inclination to the cam ring 8. 25 The pivot 12 is at the outer end of the cam and out beyond the cam ring 8 and needle butt circle.

The movement of the cam inwardly is limited by a tongue or projection 14 at the 30 point of the cam fitting in a recess in the cam ring, the under side of the tongue being inclined inwardly and upwardly, and the recess in the cam ring being formed to correspond. This construction not only provides a stop, but it also provides a flush 35 joint between the point of the cam and the horizontal upper edge of the cam ring for the unobstructed passage of the needle butts thereover.

40 Coöoperating with the needles are the jacks 15. These have one length of butts. They are placed under every other needle, in the slots of the cylinder, throughout the entire needle circle. These butts slide in 45 a cam groove 16 in the plate 16° . This cam groove has a Λ -shaped portion 17 adjacent the pivoted section 10 of the cam ring. The action of the parts is as follows: Supposing the point has been reached in the knitting 50 where it is desired to make the non-raveling course. The inclined radially movable cam 7 is adjusted inwardly one step while the short butt needles are passing it, it being understood that normally this cam is set 55 out beyond the path of the long butts. When the cam is moved inwardly one step it comes against the end faces of the short butt needles, and in this position it engages over and lowers the long butt needles when 60 they come around, and owing to the short butts having passed the cam, said cam will take another step inward and will now lower these short butt needles when they come around, and thus all the needles 65 throughout the circle will be lowered by the

cam 7 to a point where they would pass the thread feeder A without taking thread. Every other needle, however, throughout the whole needle circle, after being lowered as just described is immediately elevated 70 again to its normal plane *d*, and this is done by the jacks riding up the cam groove 17 and pushing the needles up, these jacks, as before stated, being under every other needle only. Those needles which are not 75 raised from their retracted position by jacks will pass under the stitch cam 4 and will be elevated by the central cam 5 $^\circ$, instead of, as in the application referred to, passing below this central cam and through 80 the way 18, described in said application, this way being closed in the present embodiment of my invention. The result is that these other needles which are advanced by the central cam 5 $^\circ$ will take the yarn 85 from the feeder A but will not be advanced far enough to get their old loops below their latches. Two new loops will therefore be present on these needles, and when these are cast off on a subsequent round, tuck 90 stitches will be formed, thus preventing breakage of this course and making the fabric here more elastic.

All the needles, when lowered by the cam 7, can pass the cam section 10, which, being 95 pivoted as above described, is turned aside by the pressure from the needle butts acting against its side 13° which, as above mentioned, is inclined to the path of said butts. The position of this cam section, when 100 thrown aside, is indicated in Fig. 3 in dotted lines. Those alternate needles which are raised by jacks are thereby restored to normal plane *d* and thus they are in position to be further elevated to take the yarn by 105 the advancing incline 4 $^\circ$.

The pivoted cam 10 does not perform any function in the above described action. The outwardly swinging movement which it is given is to remove it from obstructing the 110 free travel onward of the lowered needles, and those which are being raised by the cam groove 17. This cam only acts to elevate needles during reciprocating knitting for making the heel and toe. Therefore, it will 115 be understood that its pivotal mounting is merely for the purpose of allowing it to be pushed aside so that the retired needles and those which have been retired and are now being elevated may pass by it. 120

It will be observed that in making this non-raveling course alternate needles are operated to knit while the other needles are advanced only far enough to make tuck 125 stitches on this run.

In removing the cam 7 from operation it is withdrawn step by step. Its first outward step takes place while it is in engagement with the long butt needles for the second time, it requiring one and a half 130

revolutions of the cylinder to complete the operations above described, though it will be understood that a number of the described non-raveling courses may be knit if desired.

This first step movement is sufficient to position the cam 7 out of line with the short butt needles when they come around, which then remain in normal plane to be advanced 10 by cam 4^x for regular knitting, and having remained in this one step position while the long butt needles are passing it, the cam takes another step movement outward as soon as the long butt needles have passed 15 and while the short butt needles are passing the cam unaffected thereby. Its second step movement carries the cam out of the path of the long butt needles, which now, together with the short butt needles, remain 20 in their normal plane for ordinary knitting.

The radially movable cam 7 is operated inwardly by a spring 19, the said cam having a shank portion 20 sliding in a bracket 21 secured to the machine frame. The cam is 25 retracted outwardly or away from the path of the needle butts by a lever 22 bearing on a pin 23 secured to the shank, said lever being connected by a rod 24 with a lever 25 pivoted to the frame at 26 and having its 30 end bearing upon the pattern wheel 27 secured to the pattern drum shaft s' of the Hemphill patent. These connections are under tension of a spring 28 which is stronger than the spring 19 and when free to exert its 35 force will overcome the tension of the spring 19 and keep the cam 7 retracted radially outward.

For setting the cam inwardly the pattern wheel 27 has a long projection 29 which lifts 40 the levers 25 and 22 and allows the spring 19 to act in forcing the cam radially inward. The projection 29 is high enough to remove the lever 22 far enough from the pin 23 to allow the cam movement sufficient to 45 carry it up to the cylinder. Its inward movement, however, is step by step, because it first hits against the end faces of the short butt needles, but as soon as these have passed and the long butts begin to ride under the 50 cam then the spring 19 will complete the inward movement of the cam to get into the path of the short butt needles. In retracting the cam the pattern wheel is moved one step sufficient to cause the lever 25 to drop off 55 of the long pattern projection 29 and to fall onto the shoulder 30. This allows the spring 28 to retract the cam 7 one step, overcom- 60 ing in this action the force of the spring 19. The pattern wheel now takes another step in 65 the arrow direction and allows the lever 25 to drop off of the shoulder 30, and this permits the spring 28 to move the cam 7 all the way out to lie outside the path of all the 70 needle butts, the lever 25 now resting on the 75 periphery of the pattern wheel.

From the above it will be seen that the cycle of operations respecting the cam 7 is as follows: It is moved in, while the short butt needles are passing it and consequently moves in one step, its movement being limited by coming against the end face of the short butts. When the long butts begin to ride under it, the short butts having passed and no longer obstructing the inward movement of the cam, said cam, under its spring 75 tension, moves all the way in. It remains in during one and a half revolutions so that it lowers all the needles acting to lower the long butt half circle first and then the short butt half circle. Now, in order to restore the 80 cam to its outward position, it will be seen that it can not be moved outwardly until after all the short butt needles have passed the cam and have been lowered. Before all the short butts have passed the cam 7, however, some of the long butts have started 85 under the cam and have been lowered so that it is now necessary to lower all of these long butt needles, otherwise they would strike the cam 4^x and cause a smash up. The cam, 90 however, is withdrawn half way out so that it will be in position to lower all the long butts, but will be out of the path of the short butts, and when these come around they will remain up in normal plane. As 95 soon as all the long butts have passed the cam it is given another outward step movement so as to get out of the path of these long butts when they come around again. This completes the cycle.

Instead of employing jacks for the needles I may use as shown in Figs. 6 and 7 needles having long tails 31, these being alternated throughout the whole needle circle with needles of ordinary construction, *i. e.*, without these tail portions.

Cooperating with these long-tail needles is the cam 17^x on the inner side of the cam ring 8^x. The needle guide walls of the cylinder are cut away to pass this cam, as shown 110 in Fig. 7.

This cam raises every other needle, *i. e.*, all the long-tailed needles so that the same result is secured as in the case of the jacks above described, that is to say, the needles 115 are divided, every alternate needle rising to take the yarn while the other needles tuck. The other parts of the mechanism remain the same as that first described including the radially movable cam 7 and the pivotally 120 mounted cam 10.

Referring to the relative arrangements of the controlling blocks on the pattern drum for operating the yarn feed and the radially movable cam 7 for dividing the needles for 125 making the starting course, I show diagrammatically in Fig. 4 the yarn finger A down in feeding position. This yarn finger is controlled by a lever 32 as in the ordinary Banner machine, pivoted at 33 and having its 130

rear arm 34 connected by a link 34^x to a lifting lever 35 pivoted at 36 and arranged to lift the yarn finger when a block 37 on the drum comes beneath the lever, all as in ordinary practice. This block 37 moves in unison with the block 29^x, 30^x, being carried by the same drum. The relation between the blocks 37 and 29^x, 30^x and the levers 32 and 25 is such that the lever 32 is lifted first, resulting in withdrawing the yarn from the needles by lifting the yarn finger A and immediately after the work has been run off the needles due to thus lifting the yarn finger, the lever 32 falls off the block 37 and places the yarn in work again by lowering the yarn finger A to the position shown in Fig. 4. This takes place before the block 29^x comes under the lever 25. Immediately after the yarn is in work again, however, the said block 29^x comes beneath the lever 25, raising it, and thus turning the lever 22 into position to allow the spring 19 to move the cam 7 radially inward, with the result that all the needles are retired by the cam 7; their latches are opened by impact of their butts against the horizontal surface 12, and then alternate needles are elevated either by the jacks or the long tails, so that a starting course of yarn will be laid against these needles, and by the action of the web holders the yarn will be sunk, positioning it so that when the other needles rise the yarn will be on the inside of the same and thus the formation of stitches will be started.

The cam 7 is withdrawn outwardly to permit all the needles to rise after one and a half revolutions have been made by the lever 25 falling off the block 29^x onto the step or shoulder 30^x and then from this shoulder onto the periphery of the cam wheel.

Other means may be provided for controlling the operation of the dividing cam 7 as in Fig. 10 of the application above described.

I claim as my invention:—

1. In a stocking machine and in combination, stitch and advancing cams, a needle raising cam between the stitch cams, and means for retiring all the needles to a level below the stitch cam, means for advancing alternate needles to pass above the advancing cam to take the yarn and knit, the other needles passing below the stitch cam and being advanced by the raising cam to take thread but not to clear their loops below their latches, all the needles then passing below the other stitch cam, substantially as described.

2. In a stocking knitting machine, and in combination, stitch cam means, restoring cams for raising the needles to normal plane, one of said restoring cams being movably mounted to allow the needles to pass, means for retiring the needles at said movable cam,

means for raising alternate needles, after being retired, to take the yarn, and means for raising the other retired needles to take the yarn but not high enough to get the old loops below the latches.

3. In a stocking knitting machine and in combination, stitch and advancing cams, an upper central guard cam, a central needle raising cam between the stitch cams, means for retiring all the needles before reaching one of the needle advancing cams, means for raising alternate needles to pass over the said advancing cam and take the yarn while all the other needles pass below the corresponding stitch cam and are raised by the central cam part way to take the yarn but not to get their loops below their latches, said actions forming a course of knitting with alternate tuck stitches, substantially as described.

4. In a stocking machine, in combination, means to lower all of the needles below yarn-taking level, means for advancing selected needles from said level to take the yarn and knit, and means for advancing the other needles to take the yarn but not to clear their loops below their latches.

5. In a stocking machine, in combination, means to lower all the needles below yarn-taking level, means for advancing alternate needles from said level to take the yarn and knit, and means for independently advancing the other set of needles to take the yarn but not to clear their loops below their latches.

6. In a stocking machine, in combination, pattern controlled means to move all of the needles to a non-yarn-taking level, means for advancing selected needles from said non-yarn-taking level to take the yarn and knit, and means for advancing the other needles to take the yarn but not to clear their loops below their latches.

7. In a stocking machine, in combination, means including cams 7 and 17 for dividing the needles and advancing one set thereof to take yarn and knit, and means including the cam 5^x adapted independently to advance the other needles to take the yarn but not to clear their loops below their latches.

8. In a stocking machine, in combination, means including cams 7 and 17 for dividing the needles and advancing alternate needles to take yarn and knit, and means including the cam 5^x adapted independently to advance the other needles to take the yarn but not to clear their loops below their latches.

9. In a stocking machine and in combination, means for dividing the needles and advancing alternate needles to take the yarn and knit, and means for advancing the other needles to take yarn but not to clear their loops and thereby to tuck, and pattern mechanisms for controlling said dividing means to make an anti-raveling course intermediate
